MILFORD G. CHANDLER, OF CHICAGO, ILLINOIS, ASSIGNOR TO CHANDLER ENGINE
VALVE COMPANY, OF CHICAGO, ILLINOIS, A CORPORATION OF ILLINOIS.

VALVE DEVICE FOR INTERNAL-COMBUSTION ENGINES.

1,139,101.

Specification of Letters Patent.

Patented May 11, 1915.

Application filed March 4, 1915. Serial No. 12,051.

To all whom it may concern:

Be it known that I, MILFORD G. CHANDLER, a citizen of the United States, residing at Chicago, in the county of Cook and State 5 of Illinois, have invented a new and useful Improvement in Valve Devices for Internal-Combustion Engines, of which the following is a specification.

My invention relates more particularly to 10 improvement in valves of the rotary or oscillatory type for controlling the inlet and exhaust of gases through a single port in the engine cylinder; and my primary objects are to provide a construction of valve which 15 shall be of simple form, economical of manufacture, and which will be maintained sufficiently cool even when the engine is operating at high speeds and under heavy loads, and by which intermixture of the fresh gases 20 with the burnt gases in the valve will be avoided.

Referring to the accompanying drawings— Figure 1 is a view in vertical sectional elevation of the end portion of an internal combustion engine equipped with a rotary valve constructed in accordance with my invention, the valve being shown in elevation. Fig. 2 is a view in elevation of the valve shown in Fig. 1, the valve being viewed 30 from one end thereof. Fig. 3 is a section taken at the line 3 on Fig. 2 and viewed in the direction of the arrow. Fig. 4 is a view like Fig. 2 viewed from the opposite end of the valve; and Fig. 5, a section taken 35 at the line 5 on Fig. 3 and viewed in the direction of the arrow.

I have devised my improvement for use more particularly in connection with a spherical valve coöperating with a packing- 40 member surrounding the port in the engine cylinder, and have therefore illustrated my invention in this connection, though without any intention of limiting it thereby.

The upper portion of a cylinder of an 45 internal combustion engine of the four-cycle type is illustrated at 6, and is formed with a hollow head 7 from which a gas-intake pipe 8, adapted to be connected with a carburetor (not shown), and a spent-gas out- 50 let pipe 9, extend at opposite sides thereof. The interior of the head 7 which forms the casing for the valve, is of general spherical

contour and contains a port 10 which opens into the cylinder 6 and forms the inlet to, and the exhaust from, the cylinder, the upper portion of the head 7 being formed with a removable and replaceable section 11, whereby the valve proper hereinafter described, may be positioned in the valve-casing 7.

The valve proper of my improved valve device is represented at 12, and in the form illustrated is a section of a sphere, mounted on the shaft 13 journaled in a bearing 14 provided on the head 7. The valve 12 contains non-communicating passages 15 and 16 which open through opposite ends, respectively, of the valve and communicate with ports 17 and 18, respectively, in the periphery of the valve 12 and with the inlet 70 and exhaust-pipes 8 and 9, respectively, these ports being so located as to cause them to successively register with the port 10 when the valve is rotated.

By the arrangement above described, gas 75 to be supplied to the cylinder for explosion therein is taken into the valve at one end thereof and discharges from the latter through the port 17 into the cylinder 6, and the burnt gas from the cylinder is discharged into the port and passage 16 and out through the valve at the other end thereof.

In the construction of valve device illustrated, the valve 12 coöperates with a packing-member 19 which is preferably metal and is located in an annular recess 20 surrounding the port 10 and opening into the valve casing 7, the end of the member 19 which is held at all times in contact with 90 the periphery of the valve 12 by any suitable spring device represented at 21, being so shaped as represented, as to conform to the spherical contour of the periphery of the valve 12.

The valve 12 may be operated in any suitable manner to time its rotation, and consequently the communication of the ports 17 and 18 with the port 10, for the introduction of charges into the cylinder 6, and the 100 exhaust of the burnt gases therefrom, with relation to the movement of the engine piston represented at 22, but as mechanism for this purpose in connection with rotary valves

in general is commonly used and is well known in the art, a description of the valve-operating means is deemed unnecessary.

The gist of my present invention consists 5 in so proportioning the passages 15 and 16 that the surface area of the inlet passage 15 will be as great as possible, and the surface of the exhaust passage 16 be as small as possible without producing undue retardation of the passage of the exhaust gases 10 through the passage 16, whereby the maximum cooling effect of the fresh gases entering the valve is utilized to maintain the valve in relatively cool condition with the manifest advantages.

In carrying out my invention, I provide 20 in the valve 12 a partition defining the passages 15 and 16, this partition which is represented at 23, in accordance with the preferred embodiment of my invention extending 25 across the interior of the valve in inclined position relative to the axis of the valve, the end of the valve 12 through which the exhaust gases discharge being partially closed by a wall represented at 24 into which 30 wall the partition 23 at this end of the valve merges as clearly illustrated in the drawings, the partition 23 being thus so disposed that the surface area of the passage 16 is relatively small compared with the surface 35 area of the passage 15, but nevertheless the cross-sectional area of the passage 16 at any point in the valve is sufficiently large to not unduly retard the escape of the exhaust gases from the valve.

It will be readily understood from the foregoing that, by forming the valve as stated above, not only is the heating of the valve reduced by reason of the reduction in 40 the surface area exposed to the exhaust gases, but by increasing the surface area exposed to the relatively cool fresh gases, the cooling effect thereof on the valve is greatly enhanced, with the result as has 45 been proven by using a valve constructed as above stated, of preventing undue heating of the valve, permitting the engine with which it is equipped to be run at exceedingly high speeds and run under heavy 50 loads without impairment to the structure or lubrication. Furthermore, by this feature the clearness between the valve and the casing may be reduced to the minimum with 55 consequent reduction of leakage from the exhaust side to the inlet side of the valve, when the engine is idling.

While I have illustrated and described my improvement as embodied in a valve of the strictly rotary type and of spherical form 60 and co-operating with a packing-member surrounding the port in the cylinder, I do not wish to be understood as intending to limit my invention to its use in such a structure, as it may be incorporated in a valve 65 of either the rotary or oscillatory type,

whether spherical or not, and with or without packing-rings surrounding the cylinder port.

By using the word "rotary" in the following claims, I wish to be understood as 70 intending to claim broadly any valve which moves about an axis and contains my improvement, whether the valve be what is commonly termed a rotary valve or an oscillatory or rocker valve.

What I claim as new and desire to secure by Letters Patent is—

1. In an internal combustion engine, the combination with its cylinder having a port serving for both inlet and exhaust and a 80 piston operating in said cylinder, of a rotatory valve controlling said port and adapted to be operated in timed relation to said piston and containing passages opening through opposite ends, respectively, of said valve and 85 through separate ports in the periphery of said valve and serving as inlet and exhaust passages, the surface area of said inlet passage being greater than the surface area of said exhaust passage.

2. The combination with an internal combustion engine having a port serving for both inlet and exhaust, of a hollow rotatory valve controlling said port and adapted to be operated in timed relation to said piston, 95 said valve containing openings in its opposite ends with an inclined partition dividing the valve into two non-communicating passages communicating, respectively, with the open ends of said valve and opening through 100 separate ports in the periphery of the valve and serving as inlet and exhaust passages, the surface area of said inlet passage being greater than the surface area of said exhaust passage.

3. The combination with an internal combustion engine having a port serving for both inlet and exhaust, of a hollow rotatory valve controlling said port and adapted to be operated in timed relation to said piston, 110 said valve containing openings of different cross-sectional areas, at its ends, with a partition dividing the valve into non-communicating inlet and exhaust passages communicating, respectively, with the larger and 115 smaller openings in the ends of the valve, said passages communicating with openings, respectively, in the periphery of the valve, the surface area of said inlet passage being greater than the surface area of said exhaust passage.

4. In an internal combustion engine, the combination with its cylinder having a port serving for both inlet and exhaust and a piston operating in said cylinder, of a rotatory valve controlling said port and adapted to be operated in timed relation to said piston, one end of said valve being wholly open and its opposite end partially closed by an end-wall, an inclined partition 125

in said valve united at one end with the peripheral wall of the valve and at its opposite end with said end-wall and dividing the valve into non-communicating inlet and exhaust passages communicating, respectively, with the larger and smaller openings in the ends of the valve and communicating with

separate ports in the periphery of said valve.

MILFORD G. CHANDLER.
